25 Claims. (Cl. 146—47)

The present invention relates to an apparatus for treating materials with compressed fluid, especially with highly compressed steam. More particularly, the invention relates to an apparatus which is especially suited for loosening the rind or skin or peel on, or for totally separating the skin from, potatoes and other edible substances. However, the apparatus of my invention is equally useful for treatment of manufactured products and goods by contact with steam or with other types of compressed fluid media.

It is an important object of the present invention to provide an apparatus which may serve as a peeling or skinning machine and which is constructed and assembled in such a way that the duration of contact between the material to be treated and the compressed fluid may be controlled with utmost accuracy.

Another object of the invention is to provide an apparatus of the just outlined characteristics whose pressure vessel in which the material is brought into contact with the compressed fluid is constructed and assembled in such a way that the fluid can be brought into contact with the material only when the material admitting and evacuating opening or openings are properly sealed from the atmosphere whereby the personnel in charge of the apparatus is protected against injury and the duration of contact between the material and the fluid may be regulated in a fully automatic way.

A further object of the invention is to provide a peeling or skinning machine of the above outlined characteristics which is constructed and assembled in such a way that the material may be discharged automatically as soon as the fluid is permitted to escape from the pressure vessel.

An additional object of the invention is to provide a novel pressure vessel for use in an apparatus of the above outlined characteristics.

A concomitant object of the invention is to provide improved actuating means for the closure which controls the opening of the pressure vessel and to construct the actuating means in such a way that the admission of compressed fluid into the internal chamber of the vessel cannot precede the closing and sealing of the opening through which the material to be treated is admitted into or evacuated from the vessel.

With the above objects in view, the invention resides in the provision of an apparatus for treating materials, for example potatoes and other agricultural products, by contact with a compressed fluid, particularly steam. The apparatus comprises a source of compressed fluid, a pressure vessel having a material admitting opening and comprising a closure for the opening which closure is movable between an open and a sealing position, and actuating means for moving the closure to sealing position in response to admission of compressed fluid to the internal chamber of the pressure vessel. The actuating means comprises a valved conduit connected with the source of compressed fluid and including a portion which communicates with the internal chamber of the vessel, and a piston reciprocably received in the conduit and operatively connected with the closure to move the latter to sealing position in response to admission of compressed fluid into the conduit. The piston seals the

2

aforementioned portion of the conduit from the source of compressed fluid when the closure is in open position and permits inflow of fluid into the internal chamber of the vessel only when the closure seals the opening.

5 The conduit normally comprises a cylinder which receives the piston, and the aforementioned conduit portion may assume the form of one or more ducts or tubular conductors which connect the internal space of the cylinder with the internal chamber of the vessel.

10 A return spring normally maintains the closure in open position so that the closure seals the opening of the vessel only when and as soon as the valve or valves in the supply conduit permit inflow of compressed fluid into the vessel. I prefer to construct the pressure vessel in such a way that at least one of its end sections is of non-cylindrical shape; for example, such end section may be of cupped, semispherical or frustoconical form to facilitate evacuation of treated material from the internal chamber of the vessel. The opening is normally located 15 in the central portion of a non-cylindrical end section.

20 The novel features which are considered as characteristic of the invention are set forth in particular in the appended claims. The apparatus itself, however, both as to its construction and its method of operation, together with additional advantages thereof, will be best understood from the following detailed description of certain specific embodiments with reference to the accompanying drawings, in which:

25 FIG. 1 is a front elevational view of an apparatus including a pressure vessel which is constructed and mounted in accordance with one embodiment of my invention, a portion of the outer frame of the apparatus being broken away;

30 FIG. 2 is an end elevational view of the apparatus as seen from the right-hand side of FIG. 1;

35 FIG. 3 is an end elevational view of the apparatus as seen from the left-hand side of FIG. 1;

40 FIG. 4 is an enlarged fragmentary vertical section through the apparatus of FIGS. 1 to 3, showing in greater detail the construction and mounting of the pressure vessel and of the actuating means for the closure which controls the material admitting opening of the vessel;

45 FIG. 4a is a greatly enlarged fragmentary axial section through a portion of the pressure vessel and through a valved discharge conduit through which spent fluid is evacuated from the internal chamber of the vessel;

50 FIG. 5 is a partly elevational and partly sectional view of a slightly modified pressure vessel and of a modified closure;

55 FIG. 6 is a partly elevational and partly sectional view of a different pressure vessel which comprises two substantially hemispherical sections;

60 FIG. 7 is an axial section through a further pressure vessel which comprises a conical section and a cupped section and wherein the cylinder of the actuating means for the closure is mounted externally on the cupped section;

65 FIG. 8 is an axial section through an additional pressure vessel which comprises two substantially conical sections and which includes a different closure movable by a piston accommodated in a cylinder which is received in the internal chamber of the vessel;

70 FIG. 9 is an axial section through a further pressure vessel wherein the cylinder of the actuating means for the closure is located in the axis about which the vessel rotates and wherein the closure is hinged to a substantially hemispherical section of the vessel and is indirectly connected with the piston by means of a link train; and

75 FIG. 10 is an axial section through a frustoconical pressure vessel which accommodates a frustoconical closure.

The apparatus of FIGS. 1 to 4a is assumed to be utilized for loosening the skin off potatoes by contact with compressed steam. This apparatus comprises a housing or outer frame 75, best shown in FIGS. 1 to 3, which accommodates a specially constructed and specially mounted pressure vessel 1 shown in full detail in FIGS. 4 and 4a. The vessel comprises a hollow cylindrical central section or course 3, a cupped upper course or section 2 which is connected to one axial end of the central section by a welded seam 5, and a substantially conical hollow lower section or course 4 whose larger-diameter upper end portion is integral with the other axial end of the central section. The section 4 bulges outwardly so as to provide a smooth transition into the lower end of the central section 3. It can be said that the sections 2 and 4 resemble portions of hollow spherical bodies.

The material of the vessel 1 is preferably a hot-pressed metallic substance.

The smaller-diameter end portion of the section 4 defines a material admitting opening 7 which communicates with the internal chamber 1a of the vessel. In the embodiment shown in FIG. 4, the opening 7 is surrounded by an annular flange 8 which is welded to the conical section 4 and which serves as a means for reinforcing the vessel. In addition, the flange 8 supports a second flange 9 for a funnel 10 through which material to be treated is admitted into the chamber 1a when the vessel assumes the position of FIG. 1. The means for detachably securing the flange 9 to the flange 8 comprises a series of connecting elements here shown as bolts 11 and nuts 12. A sealing washer 13 which is interposed between the flanges 8, 9 may be engaged by a closure or cover 14 which is accommodated in the internal chamber 1a and which serves to expose or to seal the opening 7. In FIG. 4, the closure 14 is shown in sealing position in which it abuts against the washer 13, and more particularly against that portion of the washer which is adjacent to the innermost zone of the upper end face of the flange 9. It is possible to omit the washer 13 and to move the cover 14 into direct sealing engagement with the flange 9.

The opening 7 is located at one axial end of the pressure vessel 1, and the other axial end of this vessel carries a flange 15 which is welded to the cupped section 2 and which is detachably connected with a second flange 15' by means of bolts and nuts in the same way as described in connection with flanges 8 and 9. The flange 15' surrounds and is rigidly secured to a cylinder 16 which extends through the flange 15 and into the internal chamber 1a. This cylinder 16 constitutes one component part of an actuating means which serves to move the closure 14 to the sealing position of FIG. 4 in response to admission of compressed steam into the chamber 1a, and this cylinder also forms part of a composite supply conduit which connects the vessel 1 with a source CF of compressed fluid; e.g., a steam generator or the like. The upper end portion of the cylinder 16, as viewed in FIG. 4, carries a flange 20 which is detachably secured to a flange 19 provided at the discharge end of a pressure-resistant pipe 17 so that the cylinder may receive steam in the axial direction of the vessel. The connecting means for securing the flange 19 to the flange 20 comprises bolts 21 and nuts 22.

The cylinder 16 accommodates a reciprocable piston 23 which also constitutes an element of the actuating means for the closure 14 and which is operatively connected with this closure by means of an elongated piston rod 24 one end of which is provided with external threads and mates with internal threads in a central bore of the closure 14. The other end of the piston rod 24 receives nuts 24a by means of which the effective length of the piston rod may be varied to insure that the closure 14 seals the opening 7 in response to a selected stroke of the piston 23. It will be noted that the piston rod 24

constitutes a direct operative connection between the closure 14 and the piston 23.

The inner end portion of the cylinder 16 carries a sleeve 25 for an annular gasket 26 which sealingly surrounds the piston rod 24 to prevent bleeding of compressed fluid but to permit axial displacements of the piston 23 in directions indicated by a double-headed arrow A. The piston is permanently biased by a resilient element here shown as a helical spring 27 which is interposed between the underside of the piston and the sleeve 25 and which tends to maintain the closure 14 in open position so that a new supply of material may be introduced into the chamber 1a or that material whose treatment was just completed may be evacuated from the vessel 1. The spring 27 acts in a sense to move the piston upwardly, as viewed in FIG. 4 (see the arrow B), so that the cover 14 assumes an open position if no steam is admitted into the cylinder 16. The piston 23 then moves toward the discharge end of the pipe 17 and comes to rest in an idle position which is indicated by a line C. In such position of the piston 23, the compression of the spring 27 is negligible and, in order to prevent excessive retraction of the piston, the apparatus preferably comprises a second helical spring 28 which is disposed around the piston rod 24 between the outer end of the sleeve 25 and the closure 14 to hold the closure against actual abutment with the sleeve. One end of the spring 28 which thus acts as a cushioning means for the cover 14 is secured to the sleeve 25.

The cylinder 16 is provided with a series of radially extending ducts 29 which provide communicating passages between the internal chamber 1a and the internal space of the cylinder. These ducts are normally sealed from the pipe 17 and hence from the source CF because the piston 23 normally assumes a position in which it extends to the line C. However, when the pipe 17 admits compressed fluid into the cylinder 16, the piston moves to the position of FIG. 4 and exposes the ducts 29 so that fluid may enter the internal chamber 1a only when the closure 14 seals the opening 7. In other words, the actuating means including the parts 16, 17, 23, 24 insures that the vessel 1 can receive compressed fluid only after the closure 14 is automatically moved to sealing position because the ducts 29 are exposed only at such times when the piston 23 has completed a stroke whose length is sufficient to insure that the closure is in sealing engagement with the washer 13.

In order to insure that the material contained in the chamber 1a is thoroughly contacted by compressed fluid which is admitted through the ducts 29, the vessel 1 is mounted in such a way that it may rotate about a horizontal axis which is perpendicular to the axis of the cylinder 16. The axis of the cylinder 16 coincides with the symmetry axis of the vessel.

As shown in FIGS. 4 and 4a, the means for supporting the vessel for rotation about a horizontal axis comprises two coaxial nipples 32, 33 which are welded to the opposite sides of the central section 3 and which are respectively connected with two hollow shafts 34, 35. Each nipple carries a flange 36 which is in face-to-face abutment with a flange 36a press-fitted onto the respective shaft, and the means for pressing the flanges 36, 36a against the respective flanges 36 comprises rings 37; bolts 38 and nuts 39. A sealing washer is normally interposed between each pair of flanges 36, 36a to prevent leakage of compressed fluid from the chamber 1a.

The shaft 34 is rotatable in an antifriction bearing 41 which is accommodated in a bearing support 40 forming part of or secured to the frame 75. The shaft 34 is formed with an axial bore 43 and with a radial bore 44 which communicates with the bore 43. The intake end of the bore 43 is connected with a supply pipe 42 which accommodates a regulating valve 63 and which is connected with the source CF so that, in response to opening of the valve 63, compressed steam may flow through the pipe 42,

through the bores 43, 44, through a pressure-resistant flexible supply pipe 49, through the pipe 17, and into the cylinder 16 to move the piston 23 in a sense to insure that the closure 14 seals the opening 7 before the piston exposes the ducts 29 and permits entry of steam into the chamber 1a. The bore 44 extends into a radial nipple 45 of the shaft 34, and this nipple carries a flange 46 which is connected by means of bolts 48 and nuts 48' with a flange 47 provided at the intake end of the flexible pipe 49. The discharge end of the pipe 49 is provided with a flange 50 which is detachably connected with a flange 51 at the intake end of the pipe 17. It will be readily understood that the pipe 42 is sealingly secured to the intake end of the hollow shaft 34, for example, by means of a stuffing box 42a or the like. This sealing means 42a permits the shaft to rotate with respect to the pipe 42 whereby the pipes 49, 17 rotate with the shaft and with the vessel 1.

It will be noted that the conduit which supplies compressed fluid to the internal chamber 1a comprises the cylinder 16, the shaft 34, and the pipes 42, 49, 17, and that a portion of the cylinder 16 (i.e., that portion which is spaced from the discharge end of the pipe 17 and which is provided with the ducts 29) communicates with the internal chamber 1a.

The apparatus further comprises a second conduit which discharges spent steam from the chamber 1a. This conduit includes the aforementioned shaft 35 which is formed with an axial bore 52 communicating with the internal space 53 of the nipple 33 and which receives a discharge pipe 54, the latter being provided with a regulating valve 64. The pipe 54 is stationary and extends through a stuffing box 55 which enables the shaft 35 to rotate with respect to the pipe 54 without any leakage of compressed fluid around the pipe.

The shaft 35 is rotatable in an antifriction bearing 57 which is received in a stationary bearing support 56 forming part of the outer frame 75, see particularly FIG. 1. The means for driving the shafts 34, 35 and for thereby rotating the vessel 1 about the common axis of these shafts comprises a pulley 58 which is non-rotatably secured to the shaft 35, a V belt 62 (see FIG. 1) which is trained around a second pulley 58a on the output shaft 61 of a transmission 60 which is mounted in the frame 75 and which is driven by a variable-speed electric motor 59.

The control system of the apparatus includes the aforementioned valves 63, 64 and a relief valve 65 provided in a pipe 66 branching off the pipe 42, see FIG. 4. The pressure of fluid passing through the valve 63 is indicated by a manometer 67 which is shown in FIG. 1.

The apparatus of FIGS. 1 to 4a operates as follows, it being assumed that the compressed fluid is steam and that the material to be treated in the chamber 1a is a mass of potatoes whose skin has to be loosened sufficiently to be readily separable from the remainder of the material in a subsequent step.

The valve 63 is closed and the valves 64, 65 are open so that the pressure prevailing in the chamber 1a equals atmospheric pressure. The spring 27 maintains the closure 14 in open position and the piston 23 is in idle position indicated by the line C in FIG. 4. The inner side of the cover 14 is then at the level of a line D shown in FIG. 4. The vessel 1 does not rotate and its opening 7 faces upwardly so as to admit a new supply of material which is being introduced through a hopper 75a shown in FIG. 1. In other words, the funnel 10 is now in registry with the hopper 75a.

The volume of newly admitted material normally does not exceed two thirds of the total capacity of the pressure vessel 1.

In the next step, the operator opens the valve 63 and closes the valves 64, 65 so that the fluid may flow from the source CF, through the pipe 42, through the bores 43, 44 of the shaft 34, through the pipes 49, 17, and into the internal space of the cylinder 16 to move the piston 23 toward the opening 7 and to advance the closure 14 to

sealing position, i.e., into engagement with the detachable flange 9 or with the washer 13. The arrow E in FIG. 4 indicates the direction of movement of the piston rod 24 when the closure 14 is advanced to sealing position. The strength of the spring 27 and the diameter of the piston 23 are selected in such a way that the spring 27 yields and permits the closure 14 to move to its sealing position when the pressure of steam flowing into the cylinder 16 corresponds to minimal operating pressure necessary to treat the material in the chamber 1a. As soon as the closure 14 seals the opening 7, the piston 23 exposes the ducts 29 and the fluid is free to enter the chamber 1a. Of course, the fluid entering the chamber 1a exerts a pressure against the inner side of the closure 14 and thereby insures that the closure bears against the washer 13 with a force which is always sufficient to prevent uncontrolled escape of fluid from the vessel 1. The total cross sectional area of the ducts 29 is correlated to the diameter of the cylinder 16 in such a way that the pressure prevailing in the cylinder is always sufficient to maintain the piston 23 in the operative position of FIG. 4 as long as the valve 63 admits steam through the composite supply conduit 42, 34, 49, 17, 16.

The vessel 1 is then set in rotary motion by starting the motor 59 or by drivingly connecting the motor 59 with the output shaft 61 of the transmission 60, whereby the material contained in the chamber 1a is agitated and is thoroughly contacted by the fluid. If desired, the motor 59 may run continuously and the operator merely connects or disconnects the transmission shaft 61 when he desires to set the vessel in rotary motion or to bring such rotary movement to a halt.

After elapse of a period of time necessary to insure that the treatment of material in the chamber 1a is completed, the operator closes the valve 63 and opens the valves 64, 65. The vessel 1 may continue to rotate about the common axis of the shafts 34, 35. As soon as pressure in the chamber 1a drops to or near to atmospheric pressure (for example, to 0.1 atmospheres absolute pressure), the spring 27 moves the closure 14 to open position (i.e., the piston moves to the line C) and the material may be discharged automatically by centrifugal force to accumulate in a funnel-shaped collecting chute 68 provided in the frame 75. This chute leads the material laterally from the apparatus (see FIG. 1) and delivers the material into a basket, into a barrel or into another type of container (not shown). If the material to be treated is a mass of potatoes which are treated by contact with compressed steam, the treatment results in loosening of the skin so that the material discharged through the collecting chute 68 may be transferred into a washing machine wherein the skin is separated by streams of a washing medium.

If desired, the vessel 1 may be brought to a halt with the opening 7 facing downwardly and, as soon as the valves 64, 65 are opened, the material is discharged by gravity feed to enter the collecting chute 68 and to advance into a collecting container. When the chamber 1a is empty, the operator causes the drive means to turn the vessel through 180 degrees so that the opening 7 faces upwardly and is ready to admit a new supply of material which is being delivered through the hopper 75a.

An important advantage of the automatic actuating means for the closure 14 is that the personnel in charge of the apparatus is protected against injury because material cannot be admitted into or evacuated from the vessel unless the pressure prevailing in the chamber 1a approximates atmospheric pressure. Thus, the closure 14 must seal the opening 7 whenever compressed fluid is free to flow into the chamber 1a. Such construction of the apparatus renders it possible to provide very simple and highly reliable automatic controls to regulate the sequence of operation and, furthermore, no damage can result from improper handling of the apparatus.

The pressure vessel 101 of FIG. 5 differentiates from

the vessel 1 of FIGS. 4 and 4a in that the pipe 117 delivers compressed fluid radially rather than axially of the cylinder 116, and that the upper end of the cylinder is closed by a plate 118. Also, the section 104 of the vessel 101 is of truly conical shape and is secured to one axial end of the cylindrical central section 103 by a welded seam 106.

The outer end portion of the piston rod 124 which extends through a slightly modified closure 114 is provided with external threads to receive lock nuts 131 which serve to adjust the effective length of the piston rod. The closure 114 comprises a conical skirt 130 which facilitates evacuation of material from the internal chamber 101a, and it will be noted that the outer side of the closure may abut directly against a slightly modified detachable flange 109.

Otherwise, the construction of the apparatus shown in FIG. 5 is the same as that of the previously described apparatus and its parts are identified by identical reference numerals.

Referring to FIG. 6, the pressure vessel 201 comprises two identically dimensioned cupped sections 202, 202a of substantially hemispherical shape. Otherwise, the construction of the apparatus which embodies this vessel is the same as shown in FIGS. 1 to 4a excepting that the closure 214 assumes a form substantially as shown in FIG. 5. The sections 202, 202a facilitate automatic evacuation of material when the closure 214 is moved to open position because the material is automatically compelled to pass through the opening, either by centrifugal force if the vessel rotates, or by gravity if the vessel is arrested in the position of FIG. 6.

In FIG. 7, the vessel 301 comprises a cupped or hemispherical section 302 and a hollow conical section 304 whose smaller-diameter end portion defines the opening 307 adapted to be sealed by a closure 314. The cylinder 316 is located externally of the vessel 301 and is secured to the section 302. That portion of the cylinder 316 which communicates with the internal chamber 301a of the vessel 301 assumes the form of tubular conductors 369 and the intake ends of these conductors are exposed automatically to permit inflow of compressed fluid into the chambers 301a as soon as the piston 323 moves the closure 314 to sealing position.

FIG. 8 shows a pressure vessel which comprises a hollow cylindrical central section 403 and two hollow conical sections 402, 402a. The cylinder 416 is accommodated in the internal chamber 401a, and the operative connection between the piston 423 and the closure 414 is of the indirect type. Thus, the closure comprises two plates 414a, 414b which are articulately connected to each other by a hinge 470, and the pintle of this hinge carries a bracket 471 which is connected to the outer end of the piston rod 424. The outer portions of the plates 414a, 414b carry rollers 472 which travel in suitable guideways provided on the section 402a. The opening 407 is bounded by a suitable sealing lip or strip 472a which is engaged by the plates 414a, 414b to seal the opening 407 when the closure 414 assumes the position of FIG. 8. The cylinder 416 is formed with ducts 429 which permit inflow of compressed fluid into the chamber 401a when the closure 414 seals the opening 407. When the closure 414 moves to its open position, the plates 414a, 414b form a structure resembling the letter V.

Referring to FIG. 9, there is shown a modified pressure vessel 501 wherein the cylinder 516 replaces the nipple 32 of FIG. 4. The closure 514 assumes the form of a lid which is hinged to the cupped section 504 of the vessel and which is connected with the piston rod 524 by a link train including a bell crank lever 573 pivotable around a pin 574 which is secured to the section 504, and a link 576 which is pivoted to the closure 514, as at 577. The link 576 carries a stop plate 576a which holds the lever 573 against further angular movement about the pin 574 when the closure 514 assumes its sealing position and closes the

opening 507 and when one arm of the lever 573 is aligned with the link 576. The piston 523 moves in a direction indicated by the arrow F and rocks the lever 573 in a clockwise direction when the cylinder 516 receives compressed fluid and, as soon as the closure 514 seals the opening 507, the piston 523 exposes the ducts 529 and permits inflow of compressed fluid into the chamber 501a.

It will be noted that the cylinder need not always be located in the symmetry axis of the pressure vessel, i.e., that the axis of the cylinder need not always be perpendicular to the axis about which the vessel rotates. Of course, the axis of the cylinder 516 may make an acute angle with the axis of the nipple 33.

FIG. 10 illustrates a pressure vessel 601 which comprises a single section 604 of hollow frustoconical shape. The opening 607 is located at the smaller-diameter end of this section. The closure 614 is also of frustoconical shape and is reciprocable by a piston rod 624 which extends into a cylinder 616 fully accommodated in the internal chamber 601a. The pipe 17 is omitted and the flexible pipe 49 is connected directly to the intake end of the cylinder 616. The conicity of the closure 614 at least approximates the conicity of the section 604.

In all embodiments of my invention, the axis about which the pressure vessel rotates preferably passes through the center of gravity of the vessel.

An important advantage of a non-cylindrical pressure vessel, i.e., of a vessel whose end sections preferably assume a cupped, conical or semispherical shape, is that the evacuation of material from such vessels is much more rapid and that no means must be provided to facilitate evacuation when the treatment of material is completed. Furthermore, since the closure is actuated in a fully automatic way, the intervals of idleness of the apparatus are reduced to a minimum so that the output of the improved apparatus is much higher than the output of all such conventional apparatus of which I have knowledge at this time. In many conventional apparatus, the closure must be manipulated by hand and the operator is never sure whether or not the pressure prevailing in the vessel is low enough to avoid injury or damage when the closure is moved to open position.

When the apparatus of my invention is used as a means for loosening the skin of potatoes or other agricultural products, the compressed fluid is preferably saturated steam which is maintained at a temperature of about 160° C., and the duration of treatment of potatoes is normally between 30-50 seconds. If a potato is subjected to a longer-lasting action of saturated steam at such temperatures, the steam not only loosens the skin but also affects the edible layer immediately beneath the skin.

As stated hereinabove, the apparatus of my invention is useful not only for treatment of agricultural products but also for treatment of manufactured products or goods whenever such products or goods must be brought into intimate contact with a compressed gaseous or liquid medium.

Without further analysis, the foregoing will so fully reveal the gist of the present invention that others can, by applying current knowledge, readily adapt it for various applications without omitting features that, from the standpoint of prior art, fairly constitute essential characteristics of the generic and specific aspects of this invention, and, therefore, such adaptations should and are intended to be comprehended within the meaning and range of equivalence of the following claims.

What is claimed as new and desired to be secured by Letters Patent is:

1. An apparatus for treating materials by contact with compressed fluid, comprising a source of compressed fluid; a pressure vessel having an internal chamber and a material admitting opening and comprising a closure for said opening, said closure being movable between an open and a sealing position; and actuating means for moving said closure to sealing position, said actuating means compris-

ing a valved conduit connected with said source and having a portion communicating with said chamber, and a piston reciprocably received in said conduit and operatively connected with said closure to move the closure to said sealing position in response to admission of compressed fluid to said conduit, said piston sealing said conduit portion from said source when the closure is in open position whereby the fluid can enter said chamber only when the closure seals said opening.

2. An apparatus for treating materials by contact with compressed fluid, comprising a source of compressed fluid; a pressure vessel having an internal chamber and a material admitting opening and comprising a closure for said opening, said closure being accommodated in said chamber and being movable between a sealing and an open position; and actuating means for moving said closure to sealing position in response to admission of compressed fluid to said chamber, said actuating means comprising a valved conduit connected with said source and having a portion in communication with said chamber, and a piston reciprocably received in said conduit and operatively connected with said closure to move the closure to said sealing position in response to admission of compressed fluid into said conduit, said piston sealing said source from said conduit portion when the closure is in open position whereby the fluid can enter said chamber only when the closure seals said opening.

3. An apparatus for treating materials by contact with compressed fluid, comprising a source of compressed fluid; a pressure vessel having an internal chamber and a material admitting opening and comprising a closure for said openings, said closure being movable between an open and a sealing position; and actuating means for moving said closure to sealing position, said actuating means comprising a valved conduit connected with said source and having a portion communicating with said chamber, and a piston reciprocably received in said conduit and directly connected with said closure to move the closure to said sealing position in response to admission of compressed fluid to said conduit, said piston sealing said conduit portion from said source when the closure is in open position whereby the fluid can enter said chamber only when the closure seals said opening.

4. An apparatus for treating materials by contact with compressed fluid, comprising a source of compressed fluid; a pressure vessel having an internal chamber and a material admitting opening and comprising a closure for said opening, said closure being hinged to said vessel and being movable between an open and a sealing position; and actuating means for moving said closure to sealing position, said actuating means comprising a valved conduit connected with said source and having a portion communicating with said chamber, a piston reciprocably received in said conduit, and a link train connecting said piston with said closure to move the closure to said sealing position in response to admission of compressed fluid to and in response to resultant displacement of the piston in said conduit, said piston sealing said conduit portion from said source when the closure is in open position whereby the fluid can enter said chamber only when the closure seals said opening.

5. An apparatus for treating materials by contact with compressed fluid, comprising a source of compressed fluid; a pressure vessel having an internal chamber and a material admitting opening and comprising a closure for said opening, said closure being movable between an open and a sealing position; actuating means for moving said closure to sealing position, said actuating means comprising a valved conduit connected with said source and having a portion communicating with said chamber, and a piston reciprocably received in said conduit and operatively connected with said closure to move the closure to said sealing position in response to admission of compressed fluid to said conduit, said piston sealing said conduit portion from said source when the closure is in

open position whereby the fluid can enter said chamber only when the closure seals said opening; and resilient means for permanently biasing said closure to open position.

- 5 6. An apparatus for treating materials by contact with
compressed fluid, comprising a source of compressed
fluid; a pressure vessel having an internal chamber and
comprising a hollow cylindrical central section, a cupped
10 section rigid with one end of said central section, a hollow
conical section having a larger-diameter end portion rigid
with the other end of said central section and a smaller-
diameter end portion defining a material admitting open-
15 ing, and a closure for said opening, said closure being
movable between an open and a sealing position; and
actuating means for moving said closure to sealing position,
said actuating means comprising a valved conduit
20 connected with said source and having a portion commu-
nicating with said chamber, and a piston reciprocably
received in said conduit and operatively connected with
said closure to move the closure to said sealing position
25 in response to admission of compressed fluid to said
conduit, said piston sealing said conduit portion from
said source when the closure is in open position whereby
the fluid can enter said chamber only when the closure
seals said opening.

7. An apparatus for treating materials by contact with
compressed fluid, comprising a source of compressed
fluid; a pressure vessel having an internal chamber and
comprising two identically configurated cupped sections
30 one of which is provided with a material admitting open-
ing, and a closure for said opening, said closure being
movable between an open and a sealing position; and
actuating means for moving said closure to sealing position,
said actuating means comprising a valved conduit
35 connected with said source and having a portion commu-
nicating with said chamber, and a piston reciprocably
received in said conduit and operatively connected with
said closure to move the closure to said sealing position
40 in response to admission of compressed fluid to said
conduit, said piston sealing said conduit portion from said
source when the closure is in open position whereby the
fluid can enter said chamber only when the closure seals
said opening.

8. An apparatus for treating materials by contact with
45 compressed fluid, comprising a source of compressed fluid;
a pressure vessel having an internal chamber and com-
prising a cupped section and a hollow conical section
having a larger-diameter end portion rigid with said
cupped section and a smaller-diameter end portion de-
50 fining a material admitting opening, and a closure for
said opening, said closure being movable between an open
and a sealing position; and actuating means for moving
said closure to sealing position, said actuating means com-
prising a valved conduit connected with said source and
55 having a portion communicating with said chamber, and
a piston reciprocably received in said conduit and opera-
tively connected with said closure to move the closure
to said sealing position in response to admission of com-
pressed fluid to said conduit, said piston sealing said con-
60 duct portion from said source when the closure is in open
position whereby the fluid can enter said chamber only
when the closure seals said opening.

9. An apparatus for treating materials by contact with
65 compressed fluid, comprising a source of compressed
fluid; a pressure vessel having an internal chamber and
comprising a hollow substantially hemispherical section
and a cupped section rigid with said hemispherical section,
one of said sections defining a material admitting
70 opening and the vessel further comprising a closure for
said opening, said closure being movable between an open
and a sealing position; and actuating means for moving
said closure to sealing position, said actuating means
comprising a valved conduit connected with said source
75 and having a portion communicating with said chamber,
and a piston reciprocably received in said conduit and

operatively connected with said closure to move the closure to said sealing position in response to admission of fluid into said conduit, said piston sealing said conduit portion from said source when the closure is in open position whereby the fluid can enter said chamber only when the closure seals said opening.

10. An apparatus for treating materials by contact with compressed fluid, comprising a source of compressed fluid; a hollow frustoconical pressure vessel having an internal chamber and a material admitting opening and comprising a closure for said opening, said closure being movable between an open and a sealing position; and actuating means for moving said closure to sealing position, said actuating means comprising a valved conduit connected with said source and having a portion communicating with said chamber, and a piston reciprocably received in said conduit and operatively connected with said closure to move the closure to said sealing position in response to admission of fluid into said conduit, said piston sealing said conduit portion from said source when the closure is in open position whereby the fluid can enter said chamber only when the closure seals said opening.

11. An apparatus for treating materials by contact with compressed fluid, comprising a source of compressed fluid; a pressure vessel consisting of hot-pressed metallic material, said vessel having an internal chamber and a material admitting opening and comprising a closure for said opening, said closure being movable between an open and a sealing position; and actuating means for moving said closure to sealing position, said actuating means comprising a valved conduit connected with said source and having a portion communicating with said chamber, and a piston reciprocably received in said conduit and operatively connected with said closure to move the closure to said sealing position in response to admission of compressed fluid into said conduit, said piston sealing said conduit portion from said source when the closure is in open position whereby the fluid can enter said chamber only when the closure seals said opening.

12. An apparatus for treating materials by contact with a compressed fluid, comprising a source of compressed fluid; a pressure vessel having an internal chamber and a material admitting opening and comprising a closure for said opening, said closure being movable between an open and a sealing position; and actuating means for moving said closure to sealing position, said actuating means comprising a valved conduit connected with said source and having a portion communicating with said chamber, a piston reciprocably received in said conduit, and a piston rod operatively connected with said piston and with said closure to move the closure to said sealing position in response to admission of compressed fluid into said conduit and in response to resultant displacement of said piston, said piston sealing said conduit portion from said source when the closure is in open position whereby the fluid can enter said chamber only when the closure seals said opening.

13. An apparatus as set forth in claim 12, further comprising means for changing the effective length of said piston rod.

14. An apparatus for treating materials by contact with compressed fluid, comprising a source of compressed fluid; a pressure vessel having an internal chamber and a material admitting opening; an annular flange outwardly adjacent to said opening; connecting means detachably securing said flange to said vessel; a closure for said opening, said closure being received in said chamber and being movable into engagement with and away from said flange to respectively assume a sealing and an open position; and actuating means for moving said closure to sealing position, said actuating means comprising a valved conduit connected with said source and having a portion communicating with said chamber, and a piston reciprocably received in said conduit and operatively connected with

said closure to move the closure to said sealing position in response to admission of compressed fluid into said conduit, said piston sealing said conduit portion from said source when the closure is in open position whereby the fluid can enter said chamber only when the closure seals said opening.

15. An apparatus for treating materials by contact with compressed fluid, comprising a source of compressed fluid; a pressure vessel having an internal chamber and a material admitting opening; a first annular flange rigid with said vessel and surrounding said opening; a second annular flange outwardly adjacent to said first flange; connecting means detachably securing said second flange to said first flange; a closure for said opening, said closure being received in said chamber and being movable into engagement with and away from said second flange to respectively assume a sealing and an open position; and actuating means for moving said closure to sealing position, said actuating means comprising a valved conduit connected with said source and having a portion communicating with said chamber, and a piston reciprocably received in said conduit and operatively connected with said closure to move the closure to said sealing position in response to admission of compressed fluid into said conduit, said piston sealing said conduit portion from said source when the closure is in open position whereby the fluid can enter said chamber only when the closure seals said opening.

16. An apparatus for contacting materials with a compressed fluid, comprising a source of compressed fluid; a pressure vessel defining an internal chamber and a material admitting opening and comprising a closure for said opening, said closure being movable between an open and a sealing position; and actuating means for moving said closure to sealing position in response to admission of compressed fluid into said chamber, said actuating means comprising a hollow cylinder having a first portion and a spaced second portion, duct means communicatively connecting said first portion with said chamber, valved supply pipe means communicatively connecting said second portion with said source, and a piston reciprocably received in said cylinder and operatively connected with said closure to move the closure to said sealing position in response to admission of compressed fluid into said cylinder, said piston being normally located between said first and second portions and permitting the compressed fluid to flow through said first portion and into said chamber only when the closure seals said opening.

17. An apparatus as set forth in claim 16, wherein said first portion of the cylinder extends into said chamber.

18. An apparatus as set forth in claim 16, wherein said cylinder is located externally of said chamber and further comprising tubular conductor means communicatively connecting said first cylinder portion with said chamber.

19. An apparatus for treating materials by contact with compressed fluid, comprising a source of compressed fluid; a pressure vessel defining an internal chamber and a material admitting opening and comprising a closure for said opening, said closure being movable between an open and a sealing position; actuating means for moving said closure to sealing position, said actuating means comprising a valved supply conduit connected with said source and having duct means communicating with said chamber, said conduit comprising a hollow shaft spaced from said duct means and connected with one side of said vessel, a piston reciprocably received in said conduit and normally located between said shaft and said duct means, and an operative connection between said piston and said closure to move the closure to sealing position in response to admission of compressed fluid through said shaft, said piston permitting the fluid to flow through said duct means and into said chamber when the closure seals said opening; discharge conduit means comprising a second shaft coaxial with said first mentioned shaft and connected with the other side of said vessel; and means

for driving one of said shafts and for thereby rotating said vessel about the common axis of said shafts.

20. An apparatus as set forth in claim 19, wherein said opening is located substantially midway between said shafts, and further comprising collecting means adjacent to said vessel for receiving material from said chamber when said closure moves to open position.

21. An apparatus for treating materials by contact with compressed fluid, comprising a source of compressed fluid; a pressure vessel defining an internal chamber and a material admitting opening; a closure for said opening, said closure being movable with respect to said vessel between an open and a sealing position; and actuating means comprising a movable portion arranged to move from a first position to a second position in response to pressure exerted thereon by compressed fluid, connecting means operatively connecting said movable portion with said closure so that when said movable portion is moved from said first position to said second position said closure is moved in response thereto from said open to said sealing position, and fluid directing means for directing compressed fluid against said movable portion at the same time as compressed fluid is admitted into said chamber so that said movable portion will automatically move said closure to sealing position whenever compressed fluid from said source is admitted into said chamber so that the chamber may receive compressed fluid only when said opening is sealed.

22. An apparatus for treating materials by contact with compressed fluid, comprising a source of compressed fluid; a pressure vessel comprising a plurality of interconnected sections including an end section of non-cylindrical shape, said sections defining an internal chamber and said end section having a centrally located material admitting opening; a closure for said opening, said closure being movable with respect to said vessel between an open and a sealing position; and actuating means comprising a movable portion arranged to move from a first position to a second position in response to pressure exerted thereon by compressed fluid, connecting means operatively connecting said movable portion with said closure so that when said movable portion is moved from said first position to said second position said closure is moved in response thereto from said open to said sealing position, and fluid directing means for directing compressed fluid against said movable portion at the same time as compressed fluid is admitted into said chamber so that said movable portion will automatically move said closure to sealing position whenever compressed fluid from said source is admitted into said chamber so that the chamber may receive compressed fluid only when said opening is sealed.

23. An apparatus for treating materials by contact with compressed fluid, comprising a source of compressed fluid; a pressure vessel defining an internal chamber and a mate-

rial admitting opening; a closure for said opening, said closure being movable with respect to said vessel between an open and a sealing position and being located in said internal chamber; and actuating means comprising a movable portion arranged to move from a first position to a second position in response to pressure exerted thereon by compressed fluid, connecting means operatively connecting said movable portion with said closure so that when said movable portion is moved from said first position to said second position said closure is moved in response thereto from said open to said sealing position, and fluid directing means for directing compressed fluid against said movable portion at the same time as compressed fluid is admitted into said chamber so that said movable portion will automatically move said closure to sealing position whenever compressed fluid from said source is admitted into said chamber so that the chamber may receive compressed fluid only when said opening is sealed.

24. An apparatus for contacting materials with compressed fluid, comprising a source of compressed fluid; a pressure vessel having an axis of symmetry, said vessel defining an internal chamber and a material admitting opening; a closure for said opening, said closure being movable with respect to said vessel between an open and a sealing position; means supporting said vessel for rotation about a second axis which is perpendicular to said first mentioned axis, said supporting means comprising a shaft connected with said vessel and having an axial bore and a radial bore communicating with said axial bore; a valved pipe connecting said axial bore with said source; a cylinder arranged coaxially with said vessel, said cylinder having a first portion communicatively connected with said chamber and a spaced second portion; a second pipe connected with the second portion of said cylinder and with said shaft so as to communicate with said radial bore; a piston reciprocably received in and normally sealing the first portion from the second portion of said cylinder; and an operative connection between said piston and said closure to move the closure to said sealing position in response to admission of compressed fluid through said pipes, through said shaft and into said cylinder, said piston permitting compressed fluid to flow through said first cylinder portion and into said chamber only when said closure seals said opening.

25. An apparatus as set forth in claim 24, wherein said opening is provided at the other axial end of said vessel opposite said cylinder.
